TUNNEL CONSTRUCTION

Original Filed Aug. 20, 1923

FIG. 1.

FIG. 2.

INVENTOR.
PIERRE ZUCCO.
BY Dewey, Strong,
Dunnend & Loftus.

ATTORNEYS.

UNITED STATES PATENT OFFICE.

PIERRE ZUCCO, OF SAN FRANCISCO, CALIFORNIA.

TUNNEL CONSTRUCTION.

Application filed August 20, 1923, Serial No. 658,236. Renewed March 19, 1927.

This invention relates to tunnel construction, and has for its object to simplify and improve the construction of concrete tunnels.

This object I accomplish by making use of 5 pre-cast forms which are light in weight, and therefore readily handled, such forms being provided with means for assembling them into the shape of a tunnel, and thereafter applying a back fill of coarser concrete 10 to take care of the stresses and weight surrounding the tunnel.

One form which my invention may assume is exemplified in the following description and illustrated in the accompanying 15 drawing, in which—

Fig. 1 shows a vertical sectional view of a tunnel constructed in accordance with my invention.

Fig. 2 shows a plan view, partly in section, of the same.

The tunnel has its sides and top wall formed of curved concrete slabs or sections 10 and 11 which are pre-cast and make comparatively thin and of a length such as to 25 permit handling without special appliances. These curved sections meet at their upper ends to form an arch and at their lower ends they rest on a floor or invert 12 which may be pre-cast in slabs or sections or poured in 30 place, as desired. Each section 10 and 11 is formed with a groove 13 at one of its curved edges so that adjacent sections may be bonded together by a filling of cement within the groove.

35 It may also be desirable to employ reinforcing rods, as indicated at 14, in each of the sections, such rods, in the case of the sections, 10 and 11, extending vertically of the slab and projecting from its upper edge 40 so as to enter a core in the opposite section, as shown in Fig. 2. It is preferable to arrange the sections so that the joints at opposite sides of the center line will be staggered.

45 When the slabs or sections are in place a concrete back filling is applied. This consists of a lean concrete or mortar which may be poured or shot into place. Such back filling may contain reinforcements 16 where

additional strength is required. The sections 50 10 and 11 may be made extremely thin, as it is only necessary that they be made strong enough to be handled and support the back filling while the latter is being poured.

Where a tunnel of the character is used 55 for carrying or conducting water only the pre-cast sections need be made of a rich or compact mixture, such as will exclude water. The back filling in such cases may be made of a lean and porous mixture, thus effecting 60 a saving in the construction of the tunnel.

The present tunnel construction permits the use of sections which may be comparatively thin and light, since they are only required to support the weight of the back 65 fill when serving to furnish the main support of the tunnel. The staggered arrangement of the sections is also a matter of some importance.

Various changes in the construction and 70 arrangement of the several parts herein shown and described may be employed without departing from the spirit of my invention as disclosed in the appended claims.

Having now particularly described my invention, what I claim and desire to secure by Letters Patent is:

1. A tunnel structure comprising in any cross-section a bottom member and side members, the latter meeting at the top of the roof and defining said roof, all of said members being thin, pre-cast units, and serving as a lining for the tunnel, and a filling of concrete covering the outer periphery of said members and occupying the space between such members and the walls of the tunnel excavation.

2. A tunnel structure comprising in any cross-section a floor, side and roof members, the side and roof members being thin, pre-cast units of cementitious material, serving as a lining for the tunnel and a support for the back filling, and a filling of concrete covering the outer periphery of said members and occupying the space between such members and the walls of the tunnel excavation.

PIERRE ZUCCO.
